US0D1069391S

(12) United States Design Patent (10) Patent No.: US D1,069,391 S
(45) Date of Patent: * Apr. 8, 2025

(54) SHOE

(71) Applicant: NIKE, Inc., Beaverton, OR (US)

(72) Inventor: Laura C. Parrett, Portland, OR (US)

(73) Assignee: NIKE, Inc., Beaverton, OR (US)

() Term: 15 Years

(21) Appl. No.: 29/903,600

(22) Filed: Sep. 26, 2023

(51) LOC (15) Cl. 02-04

(52) U.S. Cl.

USPC D2/977

CLAIM

The ornamental design for a shoe as shown and described.

DESCRIPTION

FIG. 1 is a front perspective view of a shoe showing my new design;

FIG. 2 is a side view thereof;

FIG. 3 is a rear perspective view thereof;

FIG. 4 is an opposite side rear perspective view thereof;

FIG. 5 is an opposite side view thereof;

FIG. 6 is an opposite side front perspective view thereof; and,

FIG. 7 is a front view thereof.

The broken line immediately adjacent to the bottom of the shaded area defines the bounds of the claimed design and forms no part thereof. The broken lines depicting the remainder of the shoe form no part of the claimed design.

1 Claim, 7 Drawing Sheets
